UNITED STATES PATENT OFFICE.

ALONZO J. GRIFFIN, OF WILKES-BARRÉ, PENNSYLVANIA.

DESIGN FOR A RAIL FOR FENCE-PANELS.

SPECIFICATION forming part of Design No. 16,939, dated October 12, 1886.

Application filed April 14, 1886. Serial No. 198,821. Term of patent 3½ years.

To all whom it may concern:

Be it known that I, ALONZO J. GRIFFIN, a citizen of the United States, residing at Wilkes-Barré, in the county of Luzerne and State of Pennsylvania, have invented and produced a new and original Design for a Rail for a Fence-Panel, of which the following is a specification.

Reference is to be had to the accompanying drawing, forming a part of this specification, in which the figure illustrates my newly-designed rail for a fence-panel.

My newly-designed rail for a fence-panel consists of a horizontal rail, A, having a vertical end, B, disposed at right angles thereto,

and having a curved hook or eye, C, at each end, and an open continuous loop, D, of approximately horseshoe shape, intermediate of the same.

I claim as my invention—

The design for a rail for a fence-panel herein shown and described, the same consisting of a horizontal part, A, and a vertical part, B, at right angles thereto, and having a curved hook or eye, and a continuous horseshoe loop intermediate of said curved ends.

ALONZO J. GRIFFIN.
